Cyanamid Company, New York, N. Y., a corpo-
ration of Maine

Application June 2, 1948, Serial No. 30,694

6 Claims. (Cl. 222—193)

1

This invention relates to a machine and method for continuously measuring the quantity of a comminuted or powdered material by compacting the powdered material to a uniform density in a trough of known cross section moving at a pre-determinable rate whereby uniform quantities of the powder are discharged.

The accurate measurement of powders is a difficult operation. It is bad enough when a given weight of the powder must be used for a particular purpose, but when it is desired that a given weight per unit of time be used, the difficulties increase markedly; and the difficulties in the uniform rate of feeding of powders have prevented the continuous operation of many processes and have been responsible for batch operations being required at a considerable increase in expense. The instant invention solves the problem by furnishing a means whereby powders may be uniformly compacted into a trough of predictable cross section, which is not necessarily uniform, and which may be adjustable so that by passing the filled trough under a doctor blade a cross sectional shape of a constant or predictable area is passed at a rate which is a controlled variable. By use of a vacuum acting through a foraminous portion of the periphery of this trough, the powder is compacted in the trough to a uniform density so that an easily predictable quantity of the powder moves with the trough. The trough is in turn driven at a uniform or predictable rate so that the exact quantity of powder passing a given point in the trough is readily adjustable and determinable. At a later point a gas pressure is used to release such parts of the powder as do not fall from gravity into a hopper or other discharge area, within the control of the operator. The device may be used as a feeding device for feeding powders of any nature into a chemical process at any desired point or may be used for feeding powders into a container or hopper or for such other purposes as may require feeding of powders at a predictable rate.

It is an object of the invention to provide a method or machine whereby finely divided powders such as flour, plaster of Paris, sugar, salt, crystalline materials, bran, ground oats, macerated feeds, cement, coal, and other materials, may be measured and discharged in accordance with the operator's desires. All such materials are herein referred to as powders.

It is a further object of our invention to provide a machine and method whereby a uniform quantity of powder may be fed per unit of time.

2

It is a further object of our invention to provide an automatic machine whereby powdered materials may be uniformly compacted into a measuring trough at a rate which is a function of such variables as the operator may desire to introduce.

The feeding of powders at uniform rates has long been considered difficult in many processes. Many powders have a tendency to bulk or compact, depending upon vibrations or jars and to pack so that the powder does not flow uniformly. Methods of feeding powders into containers have included such devices as belts operating under a diaphragm so that a constant cross section of powder is allowed to remain on the belt; screw type feeds and others have been used. A constant volume of powder was carried by a given point, but being as the powder was not uniformly compacted, undesirably large variations in the quantity of powder being passed were thus introduced into the operation.

We have found that powders in general may be uniformly compacted by means of a vacuum. When the air or other gas is removed, the particles of the powder flow uniformly and smoothly into contact with one another. By this, our invention, the powders are compacted by means of a vacuum to a uniform density. But being at a uniform density the mass is determined as a simple direct function of the volume and accordingly by suitable selection of doctor blades, cross sectional areas, and speeds, the rate of delivery of the given mass is easy to determine. For many types of operation where it is desired that a considerable variation in rate of feed be easily accomplished, it is desirable that both the cross sectional area of this volume and its length, that is the speed of the trough, be variable in order that greater flexibility may be obtained. Where this flexibility is not necessary or desirable either the cross sectional area or the speed of movement into the trough or both may be fixed. In some cases it may be desirable to drive the trough direct from some other mechanism so that the rate of delivery will be proportioned to the speed of such other mechanism. For example, the rate of addition of salt to a bath may be governed as a direct function of the pumps feeding the bath by gearing the feeder to the pump shaft. Additionally, Geneva, square gears, elliptical gears, planetary systems, eccentric ratchet systems or any other system of mechanical linkages may be used which will give the desired relationship between the rate of drive of the feed trough and the rate at which any other mechanism is driven.

45
50
55

Various expedients along this line will suggest themselves to those skilled in the art. Additionally, the rate at which the trough is driven may be controlled through a positive infinitely variable gear box which may be controlled by any desirable or adjustable or controlled means.

Various methods may be used to vary the volume of the trough per unit of length. For some particular purposes it may be desired that the bottom of the trough be partially pocketed or have peculiar shaped relationships which may be incorporated for special purposes. For most purposes it is most convenient that a substantially rectangular cross sectional area be used with the bottom of the rectangle as the foraminous material and with either the top or one side adjustable to vary the cross section. The doctor blade may slide up and down in the trough so that the depth is varied, which is most convenient for variation while operating, or with certain types of powders it may be more desirable that a constant depth may be used, and accordingly a variable cutoff be used such as is later described in detail. Numerous other advantages, objects and variations of our invention will be apparent as it is better understood from the description in the specification and accompanying drawings. Obvious mechanical equivalent uses will be readily apparent to those skilled in the art upon reading this disclosure.

Figure 1 shows a side view of the complete machine.

Figure 2 is a front view showing a particular drive mechanism, certain details of a micrometer depth adjustment and a particular powder agitating system.

Figure 3 is a cross section taken on the line 3—3 of Figure 2, showing a specific internal construction of a specific filling trough.

Figure 4 is a section taken along line 4—4 of Figure 1, showing in more detail the interior of the filling mechanism with particular reference to valve members and air and pressure manifolds.

Figure 5 is a top view of the mechanism.

Figure 6 is an alternative construction using sintered metal with an adjustable side, or cutoff on the surface of the drum.

Figure 7 is a section taken along line 7—7 of Figure 6 showing the adjusting slide.

Our device comprises essentially a moving member in which there is a trough to be filled with powdered material which is being measured or fed. A particular modification is shown in Figures 1 to 5 in which the trough is contained in the periphery of a drum 11. The drum 11 is mounted on a shaft 12 which is rotatably journaled in supports 13. The drum may be fastened to the shaft by means of a key 14 and set screw 15. The drum may be driven through the shaft by a drive chain 16 and sprocket wheel 17 from any suitable source of power. The drive mechanism by which the sprocket is driven may be either one which rotates the drum at a constant speed or one which causes the drum to rotate in accordance with any desired speed cycle. The drum is hollowed, as shown in Figure 4, having but one support wall journaled to the shaft.

In the face of the drum is formed a groove. Through the bottom of this groove are apertures 18 through which air or an inert gas may be evacuated and through which a suitable source of air or other gas by pressure serves to eject materials. Upon the surface of this groove is a foraminous material 19. This foraminous material may consist of a uniform layer of felt, of sintered

glass, of sintered metals, paper pulp, woven fabrics, or screens. The mesh of this foraminous material should be such that air or other gas may comparatively readily flow through, but yet the flow of the filled material is prevented. The porosity of this foraminous material may be much finer for materials such as flour or finely powdered starch than for coarser materials such as sugar or salt. A material may be readily selected which is sufficiently fine to prevent the influx of whatever material is to be filled but at the same time allow sufficient flow of gas so that the powdered material is uniformly packed and retained in position by vacuum and released by gas pressure without the passages through the foraminous material becoming blocked or obstructed. As shown in Figure 4 there is a fixed shoulder 20 on the drum itself and a replaceable shoulder rim 21 which is held in position by screws or other suitable fastening means. It is desirable that this rim be removable so that the foraminous material may be more easily cleaned, assembled and replaced. The shoulders 21 and 20 and the foraminous material 19 form a trough 22 which is filled with the powdered material in operation.

The depth of the trough is not normally critical but must be consistent for uniform operations. Above the drum there is positioned a hopper 23 which may be fed by a charge chute 24. The hopper itself, may be adjustable. For some operations the hopper may be fixed in relationship to the drum so that all variations in rate of delivery are based upon changes in the rate of rotation of the drum, but for a more flexible apparatus as here illustrated, it is desirable that the hopper be adjustable. As shown in the drawing the hopper is supported by a hopper carrier 25 which hopper carrier in turn is supported by carrier shoes 26, which may be made integral therewith, which ride on the surface of the drum assembly. The hopper carrier is held in slots 27 in the supports 13, previously referred to, by means of a shaft member 28 made integral therewith. The carrier shoes are held firmly against the drum by means of the hopper positioning springs 29. As so constructed the hopper carrier floats on the surface of the drum riding on the carrier shoes and flexibly positioned by the spring so that the relative positioning is constant. In this carrier, riding between suitable guide rods and bushings 30, is the hopper itself. The hopper is vertically positioned in relationship to the carrier by means of a micrometer nut 31, positioned between anvils 32, carried by the hopper carrier and shown as integral therewith. The micrometer nut has positioned therein a micrometer screw 33 which is in turn fastened to the hopper itself by means of a stub 34. There may be an index 35 to assist in positioning the micrometer nut in the same relative position for adjustment, in accordance with the operator's desires. As so constructed, the hopper itself may be caused to ride up and down between the guide rods and bushings 30 in an accurately positioned relationship thereto. The bottom of the carrier rides in the trough to prevent lateral motion and has attached thereto a doctor blade 36. It is preferred, but not necessary, that this doctor blade and the bottom of the hopper be of the same relative height with respect to the foraminous material, so that as the drum rotates the powdered material will fill the trough completely and be scraped off to a uniform height by means of this doctor blade. Whereas the doctor blade may be made

integral with the hopper, it is usually more desirable to make it as shown as a separate member so that it may be kept sharpened, and with different materials the exact angle of attack may be modified to give a smooth, sharp, even cut.

Rotating within the hopper is a spider 31 which is suitably fastened on a shaft 39 which is journaled in bearings 38 and driven by a suitable belt drive 40, so that in operation the spider is caused to rotate through the powdered mass contained in the hopper to prevent bulking, caking and uneven flow of the powder.

Inside the drum and floating on the surfaces thereof is a stator 41. The stator is prevented from rotating by means of a positioning screw 42 in a positioning slot 43, or other suitable means. The stator is drilled to accommodate the shaft and rotates with relationship thereto. The stator fits in the drum and bears on the outer surface thereof with a peripheral seal 44. This peripheral seal member which may be made of Micarta (a phenyl formaldehyde resin containing fabric as a filler) or other suitable material, is fastened firmly to the stator and slides on the flat side of the drum, in a substantially air tight relationship thereto. On the inner surface of the stator, riding against an inner surface of the drum is an inner seal member 45, which may also be made of Micarta and which serves to prevent air from leaking around the shaft and into the vacuum and pressure chests. Joining the two circular seal members are radial seals 46. As shown in Figure 3 there are four such seals extending from the inner seal member to the peripheral seal. These seals may also be made of Micarta and may be, if desired, urged against their bearing members by individual springs although normally, if precisely constructed, such springs are not necessary. The entire assembly is held in contact with the surfaces of the drum by a spring 47. The four radial seals and two annular seals form a vacuum chest 48 and a pressure chest 49. Gases are conducted from the vacuum chest by means of a vacuum connection 50 and air or other gas may be used in the pressure chest being conducted thereto by a pressure connection 51. The periphery and side of the drum may be covered by a shield 52 which for convenience in operation may be made of Lucite or other transparent materials. It is not necessary that the entire surface be covered as a hopper may be used beneath the drum, but by having the entire surface covered all powders are trapped to insure their dropping through the discharge opening 53 and dust is prevented from escaping into the room and contamination of the measured materials is prevented.

In operation, powders or fine materials are fed through the charge chest 24 into the hopper 23. This feed may be by gravity as when the hopper is filled it will prevent additional material from feeding through the chest, insuring a reasonably consistent powder pressure head. The powder in the hopper is kept from bulking or channeling by means of the spider rotating which insures a comparatively uniform feed of the powder against the foraminous material in the trough. A vacuum through the vacuum connection which acts in turn through the vacuum chest and the foraminous surface of the drum pulls the powder into a uniformly packed layer in the trough which is cut off at an adjustable uniform height by the doctor blade 36. Accordingly, a volume of known size is generated with each rotation of the drum thereby insuring that a certain volume of pow-

der is discharged with each rotation; and because of the uniform packing resulting from the use of vacuum, a uniform density is maintained thus giving an extremely uniform rate of flow of the powdered material under the doctor blade.

At the bottom of the assembly is the pressure chest, containing a gas under pressure, which acts through the foraminous layer as it passes thereover, thus ejecting all powder which has not previously fallen by gravity. As will be obvious from close inspection of the drawings, by adjusting the height of the doctor blade the thickness of the feed layer may be readily altered so that a considerable variation in feed may be accomplished at a uniform rate of rotation. It is additionally desirable that the sprocket wheel and drive chain be driven by a variable speed drive, as for example by any of the well known positive infinitely variable drive systems, so that the feed drum may be rotated at such speed as is desired by the operator. Obviously the drive mechanism may be geared to rotate at different speeds during this operation, so that filling rates of feed may be maintained to cooperate with any specified operational cycle.

An alternative construction is shown in Figures 6 and 7 in which an adjusting slide 57 is adjustably mounted in the bottom of the hopper so that it may be inserted part way across the surface of the foraminous material, thus in effect using only a portion of the width of the trough. This gives additional flexibility that may be used to permit a constant depth of powder to insure compacting to the most efficient thickness of layer. The adjusting slide is shown as being clamped between adjusting screws 58 so that it may be laterally positioned. In this modification the use of a sintered metal as a foraminous material is particularly useful because the surface of the sintered metal may be turned or ground to an extremely accurate surface so that the adjusting slide may more accurately cooperate therewith. In the modification as shown in Figure 7, the front edge of the hopper serves as a doctor blade.

If fine powders are used, it may be necessary that auxiliary air inlets be formed in the hopper slightly above its point of contact with the drum, or that the spider be made hollow with air bleeds, so that the powder is kept aerated. Otherwise the powder may pack to the bottom of the hopper and jam the feed.

Various other modifications of this apparatus will suggest themselves to those skilled in the art and such modifications as are necessary but of minor variance of the apparatus disclosed and illustrated, are regarded as within the scope of this, our invention, in which we claim:

1. A machine for discharging powdered material at an adjustable and uniform rate comprising a traveling trough of substantially uniform but adjustable cross section, means for causing said trough to travel at a uniform but adjustable rate, a bottom portion of said trough of a foraminous material, vacuum means acting through said foraminous material for compacting a powdered material into said trough during a portion of said travel, gaseous pressure means for ejecting said material from said trough during a second portion of the travel of said trough, a hopper placed in juxtaposition to said trough and adjustable in relation thereto, a doctor blade portion of said hopper, whereby a portion of said hopper will function as a doctor blade, thereby striking off the contents of said trough at a uniform but adjustable height, and micrometer ad-

justment means whereby the position of said hopper may be varied.

2. A machine for the delivery of powdered particles comprising a circular conveyor trough adapted to be moved at an adjustable predetermined rate, a foraminous means comprising at least the bottom portion of said trough, manifolding means cooperating with said foraminous means, a doctor means adjustably positioned above said trough whereby the contents of the trough may be uniformly compacted into said trough and struck off at a desired height in said trough, and adjustable means positioned to laterally move across at least a portion of the bottom surface of said trough, whereby the effective width of said trough may be varied.

3. A machine for discharging powdered material at a uniform rate comprising a travelling trough of adjustable uniform cross-section, means for causing said trough to travel at a uniform rate, a foraminous material comprising at least part of the bottom portion of said trough, a hopper placed in juxtaposition to said trough, vacuum means acting through said foraminous material during at least a portion of the travel of the trough under said hopper, thereby uniformly compacting a powdered material in the hopper into said trough during said portion of said travel, gaseous pressure means for ejecting the material from the trough during a second portion of the travel of the trough, and doctor means adjacent said trough to uniformly strike off the contents of said trough, and means for adjusting the rate of cross-section of trough travel beneath said doctor means.

4. A machine for discharging powdered material at a uniform rate comprising a travelling trough of adjustable cross-section, means for causing said trough to travel at a predetermined rate, a hopper in juxtaposition to said trough for feeding a powdered content into said trough, a foraminous material forming at least part of the bottom of said trough, a doctor means to strike off evenly the powdered material in said trough, vacuum means acting through said foraminous material for uniformly compacting a powdered material into said trough during the portion of its travel under said hopper, and gaseous pressure means for ejecting material from said trough during a second portion of the travel of said

trough, and means for adjusting the rate of cross-section of trough travel beneath said doctor means.

5. A machine for discharging powdered material at a uniform rate comprising a travelling trough of adjustable uniform cross-section, means for causing said trough to travel at a uniform rate, a foraminous material comprising at least part of the bottom portion of said trough, a hopper placed in juxtaposition to said trough, vacuum means acting through said foraminous material during at least a portion of the travel of the trough under said hopper, thereby uniformly compacting a powdered material in the hopper into said trough during said portion of said travel, gaseous pressure means for ejecting the material from the trough during a second portion of the travel of the trough, and adjustable doctor means adjacent said trough to adjustably and uniformly strike off the contents of said trough.

6. A machine for discharging powdered material at a uniform rate comprising a travelling trough of adjustable uniform cross-section, means for causing said trough to travel at an adjustable rate, a hopper in juxtaposition to and cooperating with said trough for feeding a powdered content into said trough, a foraminous material forming the bottom of said trough, a doctor means to strike off evenly the powdered material in said trough, vacuum means acting through said foraminous material for uniformly compacting a powdered material into said trough during the portion of its travel under said hopper, and gaseous pressure means for ejecting material from said trough during a second portion of the travel of said trough.
